UNITED STATES PATENT OFFICE.

HENRY K. SANDELL, OF CHICAGO, ILLINOIS, ASSIGNOR TO HERBERT S. MILLS, OF CHICAGO, ILLINOIS.

PHONOGRAPH.

1,308,450.

Specification of Letters Patent. Patented July 1, 1919.

Application filed July 23, 1918. Serial No. 246,288.

To all whom it may concern:

Be it known that I, HENRY K. SANDELL, a citizen of the United States, residing at Chicago, in the county of Cook and State of Illinois, have invented a new and useful Improvement in Phonographs, of which the following is a specification.

The present invention relates to improvements in phonographs and will be fully understood from the following specification, taken in connection with the accompanying drawings. In these drawings, Figure 1 is a section through a phonograph cabinet of conventional form, showing in side elevation, and partly in vertical section a phonograph construction in accordance with my invention; Fig. 2 is a vertical transverse section through the diaphragms and taken substantially on the line 2—2 of Figs. 1 and 3; Fig. 3 is a horizontal section through the lower portion of the phonograph cabinet showing the mounting of the twin sound-chambers or horns therein; Fig. 4 is a top plan view of the needle-arms and related structures; Fig. 5 is a bottom plan view of the needle-arms; Fig. 6 is a longitudinal vertical section through the needle-arm taken on the line 6 of Figs. 4 and 5; Fig. 7 is a side elevation of the relatively movable needle-arm and Fig. 8 is a bottom plan view of the same; Fig. 9 is a section on the line 9—9 of Fig. 7; Fig. 10 is a section on the line 10 of Fig. 1; Fig. 11 is a section on the line 11 of Fig. 1; Fig. 12 is a detailed perspective view of the adjusting cam; Fig. 13 is a detailed perspective view of the adjusting lever; Fig. 14 is a section on the line 14 of Fig. 1; and Fig. 15 is a section on the line 15 of Fig. 2.

By way of introduction it may be said that the phonograph of the present invention is what may be described as a twin-instrument—that is, it comprises two independent sets of reproducing and amplifying devices, including needle, reproducer and sound-box or horn, combined to form a single instrument, the two needles being held in a common swinging arm and operating tandem fashion in the same record groove. According to this general plan the instrument is constructed as follows. The numeral 20 designates a cabinet, which may be of the usual form and serving to house the motor by which the table-shaft 21 is driven. The disk-table 22 carried by this

shaft supports and drives a disk-record in the usual manner. Beyond the periphery of the table 22 the cabinet-top is apertured as at 23 and over the aperture is fitted a base-plate 24 which carries a pair of downturned, opposed elbows 25—26. Within the opposed ends of these elbows there is journaled for swinging movement about a horizontal axis a fitting 27 which in external form resembles an angular cross-coupling but which, in fact, consists of a pair of 90° elbows, one of which, designated 27^a, is disposed vertically and the other of which, designated 27^b, is disposed horizontally or, rather, at a slight inclination to the horizontal, as shown in Fig. 6. As will later appear, the vertical and approximately horizontal ends of the elbows 27^a and 27^b are connected, respectively, with the two diaphragms, conducting the sound vibrations from each diaphragm to the appropriate horn. The twin horns, designated 28 and 29, are connected with the downturned ends of the elbows 25 and 26, respectively, and may be arranged side by side within the cabinet, as shown in Fig. 3.

The outwardly-turned end of the elbow 27^b has secured thereto a curved pipe 30, the outer end of which is return-bent to lie in alignment with the upturned end of the elbow 27^a. The double-diaphragm-carrying head designated 31 lies between the opposed ends of the pipe 30 and the elbow 27^a and is provided with alining nipples, which are journaled in these opposed passages, so that the diaphragm head as a whole may swivel or pivot in a horizontal plane. Since the fitting 27 making up the double elbow is itself swiveled on a horizontal axis in the opposed ends of the stationary elbows 25, 26, it will thus be seen that the diaphragm head is, in effect, universally-jointed to the base of the phonograph, the record movement being accomplished without disturbance of the connections between the diaphragm-head and the twin-horns.

The diaphragm-head 31 preferably has formed as an integral part thereof a needle bar support 32 which extends horizontally outward over the face of the table, being susceptible of traveling over the said table and movable toward and away from the same by the use of the universal-joint construction described. One of the two needles employed in the present phonograph is

mounted in a support which is carried directly upon the end of the needle bar support 32. This needle-support or needle bar, designated 33 and which carries the outer 5 or left-hand one of the two needles shown in Fig. 1, is, functionally speaking, of the nature of a bell-crank, its central portion being journaled for the slight rocking movement required upon two vertically alining 10 pins 34 secured in an end-face of the support 32. The needle bar 33 is held upon the vertical axis passing through the two pins 34 by a pair of screws 35 disposed on opposite sides of the pins and engaging laterally projecting spring arms 36 secured to the central portion of the needle bar. The needle proper is secured in the usual manner in an outwardly projecting arm of the needle bar 33 while a second, laterally projecting arm serves for the attachment of a 15 tension-and-compression member 37 in the form of a relatively thin, flexible, soft iron wire, which extends inwardly along the length of the arm 32 and is attached at its other extremity to the center of the lower diaphragm 38, making an acute angle with the plane of the latter, as shown in Fig. 6. The diaphragm 38 is secured to the lower portion of the double diaphragm-head in 20 the usual manner.

The second of the two needle-bars employed in the present construction, designated 39, and shown in detail in Fig. 9, is of the same general construction as the 25 needle-bar 33 heretofore described. Instead of being secured directly to the support 32, however, it is attached to the end-face of an auxiliary support 40 which lies within the support 32 and is loosely journaled 30 thereon by a pin 41. In order that the auxiliary support 40 may have the required freedom of movement on its pivot-pin there is interposed between the pin and the support a felt or other resilient bushing 42 (Fig. 14), and washers or gaskets of the same material, designated 43, are interposed between the side faces of the arm 40 and of the main support 32. By this construction the auxiliary support 40 is in effect universally-jointed for a very limited movement with 45 respect to its carrying support 32. The movement of the support 40 with respect to the support 32 is limited within the required range by a hook-shaped projection 45 which lies over and embraces the support 32, as shown in Fig. 9. The needle-bar 39 is connected by a wire 46 with the upper diaphragm 47 of the double diaphragm-head, this construction being identical with that 50 heretofore described.

The phonograph construction is completed by the means for effecting the tracking of the two needles in the same groove when starting to play a record. The mechanism for accomplishing this purpose con-

sists of an adjustment cam secured to the support 32 and means for determining the position of the needle-bar 39 relative to the needle-bar 33 through this cam. The adjustment cam mentioned, which is designated 48 and shown in Figs. 11 and 12, is pivoted upon and held frictionally in engagement with the face of a projection 49 formed on the main needle-bar support 32. For coöperating with this cam there is provided a thumb-lever 50, the body of which lies parallel with the lower face of the support 32 and is pivoted thereto by a screw 51 (Fig. 1). The end of the thumb-lever 50 in front of the pivot-point is adapted to bear upon the needle-bar 39. Disengagement of the adjustable thumb-lever 50 from the needle-bar 39 is insured by a wire spring 52 fastened to the thumb lever and extending inwardly along the support, and bearing against a depending pin 53 secured midway of the support 40, the arrangement being as shown in Fig. 5. One end of the thumb-lever 50 is upturned to lie opposite the face of the cam 48, and this end carries 85 a contact point 54, which lies in the path of the cam surface. It will be understood that the adjustable cam 48 may be marked in any suitable manner to indicate its proper adjustment for the playing of records of 90 any size.

The phonograph construction described in the foregoing is operative as follows. A disk-record of the lateral-vibration type and adapted for coöperation with the 100 needle-bars described, being in place upon the table 22, the first act to be performed is the proper setting of the two needle-bars so that they will enter the same groove, which is accomplished as follows. The cam 105 48 is turned to the proper adjusted position for the size of record in question. The upper end of the thumb-lever 50 is now moved toward the cam 48 and until the pin 54 engages the cam surface. During this 110 movement of the thumb-lever the needle-bar 39 will have been held in contact with the outer end of the thumb-lever by the wire spring 52, and the support 40 will therefore be moved laterally upon its loose 115 pivot pin 41 until the needle-bars 33, 39 lie in such a position that they will both enter the same groove of the record. The operation described is conveniently effected simply by the act of grasping the needle-bar support by the projection 49 thereon, the thumb squeezing the lever 50 against the cam, while the needle-bar support as a whole is lifted prior to bringing the needles into contact with the record. Upon lowering 120 the needle bar support so that the two needles contact with the record, both of them enter the same groove therein, one needle leading the other by a distance of, for example, one-fourth inch.

The thumb-lever 50 is now released and by the tension of the spring 52 bearing against the pin 53 it will in general move out of contact with the needle-bar 39 to allow 5 the needle held therein to freely follow the record groove. The machine is now in normal operation, and in such operation the wires 37 and 46, independently actuated by the two needle-bars 33, 39 will in turn independently 10 actuate the diaphragms 38, 47.

The resultant tones produced in this manner by the two diaphragms independently of one another are transmitted through the separate conduits heretofore described to the two horns 28, 29, with the resultant production 15 of a volume of sound which is just twice that obtainable by the use of a single needle. Although the two needles which are simultaneously operative according to my invention 20 cannot in practice occupy the same point in the record groove, the necessary slight spacing between the needles is found to have no appreciable effect upon the tones produced.

As the needle-bar support moves across 25 the face of the record in the act of reproducing the same, it will be apparent that the relative positions of the needle-bars 33, 39 must change to a small extent due to the decreased circumference of the record groove. 30 This required freedom of relative motion is attained by the use of the independent support 40, loosely pivoted at 41. The mass of the support 40 and, consequently, its inertia, is so great that it is relatively immovable 35 laterally on its pivot to the vibrations of the needle-bar 39 which it carries, but it may move on its pivot 41 to accommodate the decreasing circumference of the record groove and furthermore, the difference between the 40 arc struck from the center 41 and from the center of the diaphragm 38, within the range of motion of the support 40 on its pivot 41, is entirely negligible, so that there is no disturbance of the tension of the wire 37 in this 45 slight swinging movement of the support 40. In practice I find it difficult to detect any difference whatever between the quality or volume of the tones produced by the needle-bars 33 and 39.

50 The construction and arrangement of the needle-bars, and the use of the relatively long tension-and-compression member connecting these bars with the angular diaphragm, forms the subject matter of my co-pending application, Serial No. 246,447 filed July 24, 1918.

While I have in the foregoing described in considerable detail a specific embodiment

of my invention, it will be understood that this is only for the purpose of making the 60 invention more clear and that the details do not in themselves constitute the invention, except in so far as they may be included within the terms of the accompanying 65 claims, in which it is my intention to claim all novelty inherent in the invention as broadly as is permissible in view of the prior art.

What I claim is:

1. In a phonograph, a pair of stationary 70 independent sound-amplifying horns, a single diaphragm-head movably mounted with respect to the said horns, two independent diaphragms carried by the said head, means forming a separate sound-conduit 75 from each diaphragm to its respective horn, and two independent needles arranged to travel in the same record-groove, one in advance of the other, each of said needles being connected with one of said diaphragms. 80
2. In a phonograph and in combination, means for supporting and driving a record, a single needle-bar support, two independently supported and relatively movable needles adjustably mounted on said needle-bar support and arranged to travel in the same record groove, one in advance of the other, and adjusting means including a cam and lever mechanism for simultaneously and positively adjusting the initial relative 90 positions of the two needles whereby they will both enter the same record groove. 85
3. In a phonograph and in combination, a double-diaphragm-head, two independent diaphragms carried by the said head, a 95 needle-bar support carried by the head; two needle-bars mounted for bodily adjustment one with reference to the other upon said needle-bar support and remote from said head, and independent motion-transmitting devices extending along the said needle-bar support and each forming a connection between one needle-bar and one diaphragm. 100
4. In a phonograph a double diaphragm head, two independent diaphragms mounted thereon, a main needle-bar support attached to said diaphragm head, a needle-bar mounted upon the end of said needle-bar support, an auxiliary needle-bar support loosely connected with said main needle-bar support 105 short of its end, a needle-bar mounted upon the end of said auxiliary needle-bar support, and motion-transmitting mechanism connecting each needle-bar with one of the said diaphragms. 110

HENRY K. SANDELL.
